UNITED STATES PATENT OFFICE

WILLIS H. SHOEMAKER, OF BUFFALO, NEW YORK

DESIGN FOR AN ILLUMINATED ORNAMENT FOR DECORATING CHRISTMAS TREES,
WINDOWS, AND THE LIKE

Application filed September 20, 1928. Serial No. 28,224. Term of patent 3½ years.

To all whom it may concern:

Be it known that I, WILLIS H. SHOEMAKER, a citizen of the United States, residing at Buffalo, in the county of Erie and State of New York, have invented a new, original, and ornamental Design for an Illuminated Ornament for Decorating Christmas Trees, Windows, and the like, of which the following is a specification, reference being had to the ac-

companying drawings, forming part thereof.

In the accompanying drawings:

The figure is a perspective view of the ornament embodying my new design.

I claim:

The ornamental design for an illuminated ornament for decorating Christmas trees, windows and the like as shown.

WILLIS H. SHOEMAKER.
